UNITED STATES PATENT OFFICE.

GLOVER E. WEBB AND FLOYD HENSON, OF PHILADELPHIA, MISSISSIPPI.

ATTACHMENT FOR TYPEWRITERS.

Application filed May 23, 1924. Serial No. 715,410.

To all whom it may concern:

Be it known that we, GLOVER E. WEBB and FLOYD HENSON, citizens of the United States, residing at Philadelphia, in the county of Neshoba and State of Mississippi, have invented certain new and useful Improvements in an Attachment for Type-writers, of which the following is a specification.

10 This invention relates to new and useful improvements in attachments for type-writers and has for its principal object to provide a means for supporting an eraser in such a position thereon as to render the same 15 accessible to the operator of a typewriter at all times, the eraser being supported on the typewriter in such a manner as not to interfere with the operation thereof.

A further object of the invention is to 20 provide an attachment for typewriters of the above mentioned character which includes a means for returning the eraser to its normal position after the same has been used by the operator.

25 A further object of the invention is to provide a device of the above mentioned character, wherein an article attaching clip is carried by the free end of the cable which is wound around a spring actuated drum 30 whereby various articles may be attached to the free end of the cable such as an eraser, or a pencil.

A still further object of the invention is to 35 provide a device of the above mentioned character, which may not only be attached to typewriters but may also be attached to desks, tables, or any other desired place.

A still further object of the device is to 40 provide a device of the above mentioned character, which is simple in construction, inexpensive, strong and durable and furthermore adapted for the purposes for which it is designated.

Other objects and advantages of this in- 45 vention will become apparent during the course of the following description.

In the accompanying drawing forming a part of this specification and in which like numerals designate like parts throughout the 50 same:

Figure 1 is a side elevation of our attachment showing the same in position on a type-writer.

Figure 2 is a front elevation of the casing

with the cover shown in section showing the 55 construction of the winding drum.

Figure 3 is a detail perspective view of an eraser showing the manner of attaching the same to the free end of the cable.

Figure 4 is a sectional view taken approx- 60 imately on line 4-4 of Figure 3, and

Figure 5 is a view showing a pencil sup- 65 ported on the clip carried by the free end of the cable.

In the drawing wherein for the purpose 70 of illustration is shown the preferred embodiment of our invention, the numeral 1 designates a casing which may be constructed of any suitable metallic material and comprises the rear or back portion 2 from which extends the side walls 3 and 4 respectively, the same being preferably semi-circular in side elevation. The rear wall 2 of the casing is provided with a suitable opening 5 therein and the extensions 6 and 7 on the upper and lower portions thereof, the latter being also provided with openings such as shown at 8 whereby the casing 75 may be supported in position on a typewriter of any conventional construction 80 such as a Remington, an Underwood, Royal, Smith, etc. An arcuate shaped cover 9 is hinged on the back portion or rear wall 2 of the casing on the lower portion thereof as shown at 10 and extends over the outer 85 edges of the side wall. A catch such as is illustrated at 11 is associated with the upper portion of the cover 9 and the upper portion of the rear wall 2 for holding the cover in the closed position over the open portion 90 of the casing.

A partition such as is illustrated at 12 is supported in the casing by means of the supporting arms 13 which extend from the side wall 3 to the partition 12, it being understood of course that the partition is preferably arranged adjacent the side wall 3 in the manner clearly illustrated in Figure 2 of the drawing. Extending centrally through the side wall and the partition is the shaft 14 and carried thereon is the winding drum 15. The drum is preferably arranged on the shaft between the side wall 4 and the partition 12 in the manner illustrated in Figure 2. A cord or cable, or any other flexible element such as illustrated at 16 is wound around the drum and has one end thereof connected thereto. The free 100 105

end of the cord extends through a suitable opening provided in the cover 9 and has secured on the free end thereof the spring clip 17, the purpose of which will herein-
5 after be more fully described.

Supported between the side wall 3 and the partition 12 is a shaft 18 and extending therearound and having one end thereof fastened thereto is a convolute spring, the construction of which is well known in the art. The opposite end of the spring is adapted to be fastened to a ring or band 19 and the latter is provided with a gear wheel 20 and the same is adapted to mesh with the cog wheel
15 21 mounted on the shaft 14 in the manner clearly illustrated in Figure 2. The purpose of the provision of the spring and the intermeshing gear wheels is to provide a means for normally holding the cord wound
20 around the drum and for further returning the article carried by the outer free end of the cord to its normal position in the manner hereinafter to be more fully described.

Secured to the cover 9 and cooperating
25 with the opening provided therein through which extends the free end of the cord is a cup shaped member 22. The purpose of this member is to provide a means for normally housing the eraser 23 which is fastened to
30 the free end of the cord by means of the spring clip 17 whereby the eraser is supported in juxtaposition to the casing in the manner clearly illustrated in Figure 1. The rear or inner face of the eraser 23 is cut
35 away as illustrated at 24 and a rib 25 is formed therein and the same tapers smaller toward one end as clearly shown in Figure 3.

The spring clip 17 is adapted to be secured to the rib 25 and held in engagement there-
40 with in the manner shown in Figures 3 and 4 whereby the eraser will be prevented from accidentally becoming disengaged therefrom. When it is desired to use the eraser, the operator merely pulls the same outwardly si-
45 multaneously placing the coil spring under tension. After the eraser has been used, and the same is released, the coil spring through the medium of the band 19 and the gear wheels 20 and 21 respectively will automatically return the eraser to its normal position
50 within the cup shaped member 22 and re-winding the cord around the drum 15. In this manner an eraser may be attached to a typewriter in a position whereby the same
55 is accessible at all times, yet supported in such a manner as not to interfere with the operation of the machine. When one eraser becomes worn, the spring clip may be disengaged from the rib and a new eraser of a

similar construction is attached to the free 60 end of the cord by means of the spring clip.

In Figure 5 of the drawing a spring clip is illustrated as supporting a pencil 26. A device of the character above described may not only be used on typewriters but may 65 also be used on desks or tables where a person uses a pencil very frequently and by securing a pencil in the manner as shown and above described, the same will not be apt to become lost and will at all times be at hand 70 for ready use. Furthermore, after the pencil has been used, the same will be returned to its normal position and out of the way of the person at the desk or table.

It will thus be seen from the foregoing de- 75 scription, that an attachment for typewrit-
ers or the like has been provided which is simple in construction, inexpensive, strong and durable and very efficient in carrying out the objects for which the same is desig- 80 nated.

While we have shown the preferred em- 85 bodiment of our invention, it is to be under-
stood that various changes in the size, shape and arrangement of parts may be resorted to without departing from the spirit of the invention and the scope of the appended claims.

Having thus described the invention, what we claim is:—

1. A typewriter attachment comprising in combination, a casing, a spring drum rotatably supported therein, a flexible element wound around said drum, the free end thereof extending through an opening provided 95 in the casing, a spring clip carried by the free end of the flexible element, an eraser having a rib provided on the inner face thereof for engagement with the spring clip.

2. A typewriter attachment comprising in combination, a casing, a spring drum rotatably supported therein, a flexible element wound around said drum, the free end thereof extending through an opening provided in the casing, a spring clip carried by the free end of the flexible element, an eraser having a rib provided on the inner face thereof for engagement with the spring clip, and a receptacle supported on the casing and cooperating with the opening provided therein through which the cord extends for normally receiving the spring clip and the eraser carried thereby.

In testimony whereof we affix our signatures.

GLOVER E. WEBB.
FLOYD HENSON.
